UNITED STATES PATENT OFFICE.

OTTO WEICHEL, OF KAISERSLAUTERN, AND WILHELM HOLLINDERBÄUMER, OF DUSSELDORF, GERMANY.

CUPOLA FURNACE.

Application filed July 7, 1927, Serial No. 204,070, and in Germany June 2, 1926.

The invention relates to a cupola furnace with two or more superimposed rows of air nozzles. In order to blow alternately with the upper and lower rows, a double air casing has hitherto been provided, one part of which was connected to the upper rows of nozzles and the other part of which was connected to the lower rows of nozzles, in addition a device was provided in order to connect the two halves of the casing alternately with the air supply. According to another construction a common air pipe in ring form was provided for the two groups of nozzles, said air pipe being connected alternately with the various groups of nozzles, and in certain circumstances with both simultaneously, by means of slide members which were however, difficult to handle.

The object of the invention is a device, which permits of connecting two or more rows of superimposed nozzles alternately or simultaneously with one air casing or pipe only, and also of adjusting sets of nozzles. The doors of the nozzles consisting of hinged lids or rotary slide members are connected for the vertically superimposed rows of nozzles with an actuating spindle, and moreover, the doors carried by each spindle are separately adjustable, this being secured by constructing the spindle with solid and hollow members in such a manner, that each carries a separate door.

In the drawing the object of the invention is illustrated by several constructional examples in elevation or in section as in Figs. 1-4.

Fig. 5 shows in elevation and plan a construction for the common adjustment of all the doors.

According to Fig. 1 the nozzles a^1 and a^2 of each row are arranged not exactly vertically above but slightly displaced with regard to each other and they are located within the same air casing b which is indicated in the drawing by the upper and lower front walls only. In the front walls of the air casing b a spindle c is mounted, which carries the doors d^1 and d^2 . The lower door d^1 is mounted upon a hollow spindle c^1 which surrounds the solid spindle c carrying the upper door d^2 , at its lower part. The whole spindle device c, c^1 is mounted above and below in the walls of the air casing b in an air-tight manner by the usual means.

A hand wheel e is mounted upon the solid

spindle c , and the hollow spindle c^1 is provided with a setscrew c^2 in order to secure it on the spindle c after it has been adjusted. The hollow spindle c^1 may also be provided with a hand wheel for easier adjustment. Upon the upper end of the spindle c a pulley e^1 for a belt or the like is mounted, by means of which the sets of spindles arranged round the furnace can be rotated from a central point.

Fig. 1 shows the doors in the position in which the lower one d^1 is opened, and the upper one d^2 is closed. By means of a corresponding angular rotation of the spindle c the position of the doors is reversed. The spindle c is situated in the horizontal projection between the nozzles a^1 and a^2 so that the view through the observation holes f and the open nozzle is not obstructed.

In Fig. 2 a constructional form is illustrated in which the nozzles a^1 and a^2 lie exactly vertically over one another. The spindle c with the doors d^1 and d^2 is situated to one side so that here also the view through the observation holes f is not obstructed. This arrangement is particularly suitable if the regulation of the air supply to the furnace is preferably to be effected in such a manner that two nozzles arranged one above the other receive air. By rotating the hollow spindle c^1 it is of course possible to keep only one door closed.

In Fig. 3 for the sake of simplicity a single spindle c is shown, upon which the doors d^1 and d^2 , constructed as sections of a cylinder are mounted; they can be secured in different angular positions by means of their setscrews c^2 . The bodies of the nozzles are also so formed, that the spindle c is located here also to one side, so that the view through the observation holes f is again unobstructed.

The upper part of Fig. 3 shows the lower door or rotary slide member d^1 closed, and the upper one opened. It will be seen from the illustration in plan that, with correspondingly chosen proportions of the slide members d^1, d^2 by means of inter-adjustment, a simultaneous opening of the nozzles can be obtained. Of course, even in this constructional form the hollow spindle or a similar device can be employed in order to be able to adjust the one slide member from externally, independently of the position of the spindle c .

According to Fig. 4 an air casing is not employed, but a so-called ring air pipe b^1 is used, from which branches b^2 are led downwardly, these branching again into four trunks b^3 which lead to four nozzles located two in the upper circle and two in the lower. The rotary control members d^1, d^2 are housed with their spindle c within the vertical portion b^2 of the pipe. The illustration in plan 10 of Fig. 4 only indicates one slide member d^1 , so that it can close either the left-hand or the right-hand nozzles of a horizontal row of nozzles in the form of a ring. By rotating the spindle with relation to the position shown in Fig. 4 through 90°, both adjacent nozzles are connected to the air supply. If the member d^1 is duplicated so that a similar rotary member is located opposite to the one shown, then both the adjacent 15 nozzles in the same horizontal row can be shut off simultaneously. The hollow spindle, of course, can also be employed, in order to be able to treat the upper nozzles differently from the lower nozzles of the same 20 group. The freedom of vision through the observation holes f is also fully preserved in this arrangement.

According to Fig. 5 a rope g runs round the pulley e^1 of the sets of spindles c mounted in the air casing b , and also runs round a driving pulley k mounted upon the vertical spindle h . The spindle h can be rotated by means of a hand winch drive h' ; a motor drive of some kind can of course be employed instead of the hand drive.

According to the detail construction of the doors the upper and lower nozzles can be opened alternately by rotating the driving spindle h to and fro; for this the constructional form according to Fig. 1 is particularly suitable.

If the doors d^1, d^2 of the constructional form according to Fig. 2 are so adjusted upon the spindle c , that they shut and open 45 together, then the spindles should be so arranged round the furnace alternately either separately or in groups, that some have their doors closed whilst others have them open. By rotating the driving spindle h to and fro the nozzles which were first closed are opened and those which were opened are closed.

With the constructional forms according to Figs. 3 and 4 the spindle h can be rotated continuously in one direction. By the adjustment of the doors d^1 and d^2 according to Fig. 1 the sets of nozzles above and below will be closed and opened alternately; if the rotary members are located above one 60 another, as shown in the plan of Fig. 4 so that they cover one another in vertical projection, then each pair of superimposed nozzles will be simultaneously opened and closed. If the separate spindles c are so adjusted that one has a certain angular ad-

vance in relation to the one next adjacent, then upon further rotation in the same direction the so-called travelling of the nozzles round the furnace is immediately obtained; this travelling of course can also be so adjusted that it is effected simultaneously from two opposite or more than two or other points and moreover always from two opposite nozzles: if, however, the doors d^1 , and d^2 are again disposed as may be seen from Fig. 2, then the travelling blowing is no longer effected at the same time in rows of nozzles lying at various heights, but at different times. The action of the draught can thus be regulated in different ways between extraordinarily wide limits, and this is even more so, if the means is employed of proportioning differently the rotary members as shown in Figs. 3 and 4 so that, assuming that their bearing spindles rotate with the same velocity, they close the nozzles for a shorter or longer time.

Since the required quantity of air always enters the furnace through a great number of nozzles and moreover through a number of rows opposite one another simultaneously, it is possible to operate with a comparatively small air pressure. Regulation is so far possible that the air which is fed in from the lower nozzles and which immediately tends to flow upwards, is turned by the streams of air from the upper nozzles towards the centre of the smelting zone, and moreover an increase in the smelting zone is obtained. A comparatively high mass of coke glowing evenly over the whole cross section of the furnace can be easily obtained, through which the molten iron drops and thus becomes very hot. Cooling of the iron can thus be easily avoided, the waste in combustion and the burning out of the furnace is reduced, and the same holds true as regards the consumption of coke and also as regards the taking up of sulphur of the iron.

By the regularity in the air supply which is afforded and particularly by that which is obtained with a motor drive and the division of the air supply, the mouths of the nozzles are kept regularly free from slag, whereby the small burning out of the furnace assists the keeping clear of the mouths of the nozzles.

Even with a motor drive for the spindles, the possibility of being able to rotate and adjust the separate spindles by hand is by no means excluded. Such a separate adjustment is of value when observation of the furnace through the special openings therefor shows that for example, the air supply should be increased temporarily at one point. In order to render the displacement of the spindles possible by means of the hand wheels, the pulleys e^1 for example can be so mounted that they only rotate the spindles by friction, and in some cases the

pulleys e^1 secured upon the spindles can be rotated against the driving means which rotates them (the steel cable g) since the latter only acts upon the pulleys e^1 by friction.

5 We claim:—

1. In a cupola furnace having a plurality of air nozzles, each nozzle being provided with a device for controlling the flow of air through the nozzle, a spindle connected 10 to said devices for simultaneously adjusting the same to regulate the flow of air, and means included in the connection to one of said devices for obtaining independent adjustment thereof.
- 15 2. In a cupola furnace having a plurality of air nozzles, each nozzle being provided with a device for controlling the flow of air through the nozzle, means for adjusting said devices comprising a rotatable spindle 20 connected to one of said devices, a sleeve on said spindle connected to another of said devices, and an adjustable connection between said sleeve and spindle.
- 25 3. In a cupola furnace having a plurality of rows of air nozzles located one above the other, each nozzle being provided with a device for controlling the flow of air therethrough, a plurality of operating means, connections from each of said means to a 30 plurality of said devices, one in each row, for adjusting said devices separately or simultaneously, and mechanism for controlling said operating means simultaneously.
- 35 4. In a cupola furnace having a plurality of superimposed rows of air nozzles, each nozzle being provided with a device for controlling the flow of air therethrough, a plurality of actuating spindles, connections from each spindle to a plurality of said 40 devices, one in each row, one of said connections being adjustable with relation to the spindle for obtaining separate actuation of the corresponding device, and means for operating said spindles simultaneously.
5. In a cupola furnace having a plurality of superimposed rows of air nozzles, each nozzle being provided with a device for controlling the flow of air therethrough, a plurality of actuating spindles, connections from each spindle to a plurality of said devices, one in each row, one of said connections being adjustable with relation to the spindle for obtaining separate actuation of the corresponding device, and means for operating said spindles simultaneously, said 55 means comprising a pulley on each spindle, a driving pulley, and a belt connecting said pulleys.
6. In a cupola furnace having a plurality of air nozzles, each nozzle being provided with a device for controlling the flow of air therethrough, a spindle, connections between said spindle and said devices for controlling the latter, said devices being arranged on opposite sides of said spindle, whereby movement of a spindle to move a device on one side thereof to air admitting position will serve to move a device on the other side thereof to air retarding position.
7. In a cupola furnace having a plurality of air nozzles, each nozzle being provided with a device for controlling the flow of air therethrough, a spindle, connections between said spindle and said devices for controlling the latter, said devices being arranged on opposite sides of said spindle, whereby movement of a spindle to move a device on one side thereof to air admitting position will serve to move a device on the other side thereof to air retarding position, and means included in one of said connections for adjusting the relative positions of said devices.

In testimony whereof we have signed our names to this specification.

OTTO WEICHEL.
WILHELM HOLLINDERBÄUMER.
